UNITED STATES PATENT OFFICE.

CLAYTON EMMETT BEDELL, OF BUFFALO, NEW YORK, ASSIGNOR TO CURTISS AERO-
PLANE AND MOTOR CORPORATION, A CORPORATION OF NEW YORK.

FLYING-BOAT HULL.

1,364,425.

Specification of Letters Patent.

Patented Jan. 4, 1921.

Application filed September 14, 1917. Serial No. 191,471.

To all whom it may concern:

Be it known that I, CLAYTON E. BEDELL, a citizen of the United States, residing at Buffalo, in the county of Erie and State of New York, have invented certain new and useful Improvements in Flying-Boat Hulls, of which the following is a specification.

The hull of my invention is an improvement over the flying boat hull disclosed in Patent No. 1,223,319, issued to Glenn H. Curtiss, April 17, 1917. It relates generally to constructional details and contemplates changes which add to the efficiency of the craft, make for increased seaworthiness, better lines and decreased weight, and which lead to better hydroplaning behavior and less frictional resistance while hydroplaning.

Of the drawings:

Figure 1 is a vertical longitudinal sectional view of the forepart of the hull;

Fig. 2 is a plan view of that portion of the hull illustrated in Fig. 1;

Fig. 3 is a vertical longitudinal sectional view of the tail portion of the hull, *i. e.*, a continuation of Fig. 1;

Fig. 4 is a plan view of that portion of the hull illustrated in Fig. 3, *i. e.*, a continuation of Fig. 2;

Fig. 5 is a front end elevation;

Figs. 6, 7, and 8 are transverse sections taken respectively on the lines 6—6, 7—7 and 8—8 of Fig. 2, and

Fig. 9 is a further section taken on the line 9—9 of Fig. 4.

The hull or body of the craft may be generally described as comprising a fore body 10 and tail 11; a step 12 formed in the hull bottom affording a line of demarcation between the two. Viewed from the side the fore body 10 is characterized by a relatively blunt nose 13, flat deck 14, and rearwardly and downwardly and thence almost horizontally rearwardly inclined bottom 15. Said bottom constitutes the principal hydroplaning area of the hull and is of the conventional V-form except in so far as hereinafter pointed out. Fin excrescencies 17 augment the hydroplaning area of the hull bottom laterally. These fins emanate from the extreme bow (which viewed in plan is relatively sharp or pointed) and widen out perceptibly toward the step. In cross section, both transversely and longi-

tudinally, the fins 17 are of substantially streamline form. Rearwardly they terminate squarely in alignment with said step.

The tail portion, unlike the fore body, is of relatively light construction. Its bottom 18 extends slightly upwardly and rearwardly from the step 12 to avoid contact with the water when hydroplaning at speed thereon and to permit of fore and aft oscillation in breaking from the water surface. The cross sectional area of the tail uniformly decreases from the step rearwardly to the stern.

Interiorly, the hull comprises the usual keelson 19, floors 20 and frames 21. The floors 20, in depth, from the bow aft to a point approximately one third of the distance from the nose to the step, increase, and thence decrease gradually for a portion of their remaining length. Several of these floors in the vicinity of the bow extend out laterally beyond the chines of the hull to the margins of the fins. That portion of the hydroplaning surface upon which landing impacts are imposed is thus strengthened materially. Moreover, the angularity of the V-bottom at this particular point is such that the continuity of the floors beyond the chines is quite practical.

Said bottom 15, although generally of the conventional V-form is characterized by an improved cross sectional form in which the acuteness of the V is relatively marked in the vicinity of the keel line and practically negligible throughout that portion of said bottom underlying the fins. As said bottom approaches the step the acuteness of the V becomes less noticeable until in the vicinity of the step it makes a salient angle in cross section (see Fig. 7). In other words, where the V-bottom is most acute in the vicinity of the keel its margins are characterized by substantially horizontal flatness and where said bottom is least acutely V-formed its margins are characterized by a noticeable upward and outward inclination. This particular type of V-bottom is especially advantageous in that the water is split in landing and in hydroplaning is split and directed laterally in a manner offering the least frictional resistance due to skin friction. Where the edges or margins of the bottom overhung, *i. e.*, dropped down below the horizontal plane

of the chines, considerable resistance would be offered by reason of the confinement of the deflected water within the concavities thus formed. The propellers are also thus 5 protected from flying spray.

The keel 22 is made in two parts. The bow keel portion commences at the top of the hull to the rear of the bow end and extends forwardly beneath the deck 14 for a 10 portion of its length to a point 23 where it is doubled back after a fashion common to this type of craft for continuation rearwardly beneath the several floors 20 to the step. The stern keel portion throughout its 15 length is rectilinear and at its forward end let through the step floor for continuation beyond the rear end of the bow keel portion to which it is united by any suitable means at a point forwardly of the step. 20 That portion of the hydroplaning bottom adjacent to the step and about which the craft oscillates in breaking from the water is thus strengthened while the continuity of both the tail bottom and the hydroplaning 25 bottom remains unbroken. At its rear end the stern keel portion is fastened to the stern post 24.

Chine stringers 25 interiorly brace the hull bottom and form with side stringers 30 26, fin hull side stringers 27 and fin edge stringers 28 a skeleton or framework around which the hull is built. As before intimated, the floors 20, except such as lie in the vicinity of the bow end thereof terminate 35 squarely in alignment with the stringers 25 to which they are mortised or appropriately fastened by other suitable means. Cap-strips 29 underlie the floors 20 and extend beyond the floor ends to the 40 fin edge stringers 28. The extended portions of the cap-strips 29 are supported by fin floors 30 which constitute prolongations of the hull floors. This continuity of the cap-strips from the keel line to the fin edge 45 stringers is such that the bottom planking, designated 31, is effectually supported throughout. Said planking is two ply, one layer of planks extending diagonally outwardly and rearwardly from the keel at 50 each side thereof and the other layer of planks longitudinally or fore and aft. The step floor 12 extends from fin edge stringer to fin edge stringer. Its depth is greatest in the vicinity of the keel and least toward its 55 opposite ends. This variation in depth is symmetrical from the keel line and such that the rear fin edges have a thickness equal only to the depth or thickness of said floor. The chine stringers, where they intersect the 60 step, are thickened as at 32 so that the step floor may be let into them without weakening the structure at this point.

Wing beams 33 and 34 are built into the hull to constitute an intimate part thereof. 65 The beam 34 (the forward beam) passes

transversely through the hull in a vertical plane forwardly removed from the vertical plane of the step and in a horizontal plane such that it may rest upon the side stringers 26. The beam 33 (the rear wing 70 beam) unlike the forward beam, passes transversely through the hull in a plane beneath the plane of the side stringers and to the rear of the step. Both beams are vertically braced as at 35, the braces extending 75 to the chine stringers 25 and as at 36, the latter braces extending respectively fore and aft, along the hull sides in such manner that both beams are directly connected with the step block and with the chine 80 stringers at each side of the hull.

At the forward end and at the tail end of the hull the frames 21 are continuously curvilinear throughout and interconnect, by way of the hull sides and deck, the floor 85 ends. Notches 37 are formed in said floor ends to receive the terminals of the frames, said terminals being indent as at 38 to overlap the floors and engage in said notches as illustrated in Fig. 6. Furthermore, the 90 chine stringers 25 are provided with beveled edges 39 of such form that the bent ends 38 of the frames 21 may contact flush therewith to prevent spreading of the frames. The intermediate frames are of a two part 95 construction by reason of the formation of a cockpit 40 and a hatch 41. The hatch covering I have designated as 42.

The extended ends of the wing beams 33 and 34 are inwardly braced as at 43 by diagonal braces. These braces form with a compression brace 44 a bridge truss of a construction constituting part and parcel of the hull. The braces, it will be noted, extend diagonally inwardly from the beam ends for 100 connection with the compression brace which (see Fig. 7) passes through the hull for lateral extension beyond the hull sides. Said compression braces also function as bulkhead stiffeners in that their location is such 105 that the bulkheads 45, of which there are preferably five, are arranged, one beneath each beam, one in advance of the foremost beam and two aft of the beam 33. Openings 46 are formed in the foremost and 110 the two rearmost bulkheads.

Both the fin edge stringers and the chine stringers emanate from a common point at the extreme bow end of the hull and extend rearwardly in substantially the same 120 horizontal plane to the step. Toward the step end the fin edge stringers are inclined slightly upwardly in such manner that the angularity of the marginal portions of the hydroplaning bottom may be somewhat 125 more noticeable toward the rear than at the bow. Furthermore, an arm hole 47 is formed in the tail structure 11 adjacent its rear end that access may be gained to the tail interior for the proper anchorage of the 130

vertical stabilizer brace (not shown) which in this model craft extends into the hull. Other features, such as the forwardly and downwardly inclined brace 48, ventilator 5 tube 49 and towline brace wiring 50 constitute but details incidental to the completely assembled hull.

What is claimed is:

1. In a hull for flying boats, chine stringers, fin excrescencies including fin edge stringers, floors arranged to extend respectively from chine stringer to chine stringer and from fin edge stringer to fin edge stringer, and fin-floors interconnecting the 10 chine stringers and fin edge stringers in substantial prolongation of the first mentioned floors, the arrangement of said floors being such that the continuous floors brace that portion of the hydroplaning bottom of 15 the hull calculated to receive the full stress of landing impacts.
2. In a hull for flying boats, chine stringers, fin excrescencies including fin edge stringers outwardly and rearwardly curved 20 from the extreme bow end of the hull, and floors continuous through the hull from fin edge stringer to fin edge stringer in the vicinity of the bow end and from chine stringer to chine stringer aft thereof.
3. A hull for flying boats including a 25 step-floor having an opening formed in it together with a keel let through said opening to continue beyond the floor without interrupting its continuity.
4. A hull for flying boats including a 30 step-floor having an opening formed in it, a bow keel portion arranged to abut said floor and a stern keel portion let through said opening to overlap said bow keel portion, said keel portions together making a 35 substantially salient angle.
5. In a hull for flying boats, fin excrescencies arranged to augment the bottom surface of the hull, a step-floor continuous 40 from the lateral margin of one fin to the lateral margin of the other, the depth of the floor decreasing symmetrically from its point of intersection with the keel line to its respective outer ends, and chine stringers of relatively increased thickness at their points of intersection with said floor.
6. A hull for flying boats including a plurality of frames having their ends inwardly bent to overlap the ends of corresponding 45 floors, the floors being notched to receive said bent portions and by reason of their 50 location beneath said bent ends tending to prevent straightening out thereof.
7. In a flying boat hull, chine stringers, frames having their ends inbent in the vicinity of said stringers, and floors interconnecting said stringers to form therewith abutments for said inbent frames.
8. In a hull for flying boats, chine stringers having their inside top edges beveled, 55 frames having their ends inbent, and floors interconnecting said stringers to form therewith abutments for said inbent ends, said ends lying flush against the beveled edges of said stringers.
9. In a hull for flying boats, fin excrescencies arranged to augment the bottom surface of the hull, and a step-floor continuous from the lateral margin of one fin to the lateral margin of the other, the depth of the 60 floor decreasing symmetrically from its point of intersection with the keel line to its 70 respective outer ends.
10. In a hull for flying boats, chine stringers, fin excrescencies including fin edge 75 stringers and floors continuous from the keel line of the hull to the chine stringers and to the fin edge stringers respectively.
11. In a hull for flying boats, an intermediate located transversely extending wing 80 beam, a transverse bulk head underlying said beam, a combined bulk head stiffener and cross brace, and braces extended diagonally inwardly from the ends of the wing beam for connection with the ends of the cross 85 brace.
12. In a hull for flying boats, opposed fin excrescencies projected laterally beyond the sides of the hull, a rearwardly facing step 90 formed in the hull bottom, a step floor continuous from the lateral margin of one fin to the lateral margin of the other, the depth of the floor decreasing symmetrically from its point of intersection with the keel line to its 95 respective outer ends.
13. In a hull for flying boats, opposed fin excrescencies projecting laterally beyond the sides of the hull, a rearwardly facing step formed in the hull bottom, a step floor continuous from the lateral margin of one 100 fin to the lateral margin of the other, and chine stringers of relatively increased thickness at their points of intersection with said floor.

In testimony whereof I hereunto affix my 110 signature.

CLAYTON EMMETT BEDELL.
